UNITED STATES PATENT OFFICE.

HENRY C. SPONHAUER, OF GALION, OHIO.

BURIAL-VAULT CLOSURE.

1,384,279.

Specification of Letters Patent. Patented July 12, 1921.

Application filed October 20, 1919. Serial No. 331,962.

To all whom it may concern:

Be it known that I, HENRY C. SPONHAUER, a citizen of the United States, residing at Galion, in the county of Crawford and 5 State of Ohio, have invented certain new and useful Improvements in Burial-Vault Closures, of which the following is a specification.

This invention has to do with burial cases 10 or what may be termed portable burial vaults of the class designed especially to receive a coffin so as to inclose and protect the latter, with the body contained therein, when the coffin in the case or vault has been 15 placed in the grave.

Among the particular objects of the invention are the provision of a vault or case of unusually rigid or substantial metal construction, the formation of the vault so as to 20 render the same practically airtight when the closure provided therefor is finally placed in position and locked, the provision of special locking means for the said closure, and the employment of other detail 25 features of construction and improvement, an understanding which will be readily had on reference to the following description in conjunction with the annexed drawings, in which:—

30 Figure 1 is an elevation and sectional view of a burial case or vault embodying the invention.

Fig. 2 is a sectional view transversely through the vault and looking toward the 35 inner side of the closure for the open end, the locking means for the closure being clearly illustrated.

Fig. 3 is a sectional view through the central portion of the closure and bringing out 40 more clearly the operating means for the locking bolts, whereby said bolts are not only slidably actuated but caused to rock for final locking and sealing compression of the closure against the open end portion of the 45 vault or case.

Throughout the following description and in the drawings similar reference characters refer to similar parts. As shown most 50 clearly in Fig. 1 of the drawings, the vault or burial case of my invention comprises a body A of metal construction closed at one end and having the other end opened but adapted to receive a closure when the vault is to be sealed for being placed in the grave. 55 The body A comprises also a suitable bot-

tom, and the closed end and the bottom are preferably united with the upper or major portion of the body by means of a double lap seam A' at the juncture of the respective edges of said parts. In order to lend 60 rigidity to the vault body, it is notable that said body is formed with transverse corrugations, shown at 1, and additionally it will be seen that the body is curved at its upper portion to provide a sort of arched form in 65 cross section. The corrugated and arched formation just described is of obvious advantage for the purpose above outlined. At its open end portion, the body A is formed with a flange 2 providing a seat 70 against which the closure B is received and locked after the coffin has been disposed in the vault or case and the two are ready to be placed in the grave preliminary to the filling 75 of the latter. The closure B conforms in its general outline or shape with the cross sectional outline of the vault body A and the locking means for said closure will now be set forth.

Mounted on the inner side of the closure 80 B are the several locking bolts 3, having a sort of radial disposition in respect to the approximate center of the closure. The bolts 3 are adapted at their outer ends to engage with the inner side of the flange 2 by the 85 provision on said bolts of locking elements 4 which directly coöperate with the flange. The bolts 3 are slidable on the inner surface of the closure B, owing to the provision of headed guiding, holding studs 5, a plurality 90 of which project from the closure and pass through slots in the bolts.

At their inner ends, the bolts 3 have racks 6 arranged in spaced relation, and at these 95 ends the bolts 3 are guided in their movement by guide lugs 7, projecting from the closure. The several bolts move rectilinearly relatively to one another and said bolts are actuated by a pinion 8 mounted to turn with the stub shaft 9, journaled on the 100 closure at its central portion. The stub shaft has a central boss 10 between which and the pinion 8 is an actuating disk 11. The disk 11 is normally disposed in a seat 12, formed on the inner surface of the closure B and said disk is adapted to turn with the shaft 9, along with the pinion 8. A nut 13 screwed on the inner end of the shaft 9 holds the parts 8 and 11 from displacement from said shaft. The shaft 9 may be 110

said to be a two part shaft in that it comprises the section designated 9 and the section 9^a at the outer portion of the section 9. The section 9^a has an enlargement 9^b which receives in a threaded socket therein the threaded outer terminal 9^c of the shaft section 9. The parts 9^b, 9^c, and 10 are largely received and operate in a casing or hollow member 14 integrally or otherwise carried by the central portion of the closure B and projecting outwardly from the latter. The outer end of the casing or member 14 has an opening therein through which the outer end of the shaft section 9^a protrudes, said shaft section being formed at this portion with a squared end for the application thereto of a wrench or some suitable turning tool. By reason of the connection between the shaft sections 9^a and 9 relative movement of these sections is enforceable under certain conditions.

With the understanding that the mounting of the locking bolts 3 relative to the studs 5 is sufficiently loose to permit of slight rocking of the bolts on said studs, whereby the bolts may act after the manner of levers to impinge the outer ends thereof against the flange 2, the operation of the locking mechanism thus far presented may be set forth.

We shall assume that the body to be preserved and protected by means of the vault or case herein described, has been placed in the vault by disposing the coffin in the latter. The closure B is then seated against the flange 2 for the final sealing of the vault or case. The operator then applies a wrench or like tool to the outer end of the shaft section 9^a and turns said section to the right. The adjacent ends of the shaft sections 9 and 9^a are in substantial abutment so that the turning action of the part 9^a causes turning of the shaft section 9, the pinion 8 and disk 11. The movement of the pinion 8, owing to its engagement with the racks 6, forces the bolts 3 outward until they lap over and engage the flange 2 on the inner side of the latter, the closure itself fitting against the outer side of the flange. The bolts have now preliminarily locked the closure against displacement and in order to give a final sealing compression action to the closure B to press it firmly against suitable packing 15 interposed between it and the flange 2, the wrench or tool engaged with the shaft section 9^a is reversed in its movement. This action results in unscrewing of the portion 9^c from the portion 9^b of the respective shaft sections 9 and 9^a. By the above operation the shaft section 9 is caused to move inward carrying with it the disk 11 and pinion 8 and causing the outer portion of the disk bearing against the inner ends of the racks 6 to force said racks inward 65 away from the closure thus rocking them

and causing the rocking bolts to act as levers for clamping the closure B firmly against the flange.

Since it is designed that once the closure B is finally sealed, the vault shall be locked against tampering as well as for rendering the same airtight, I provide an auxiliary lock for the bolts 3 in the form of an automatically locking dog 16 pivoted to the inner side of the closure B at 17. This dog operates in an opening in one of the bolts 3, being actuated by a spring 18 which normally tends to throw the dog into engagement with an inclined rack 19 at one side of the opening of the bolt just above mentioned. To maintain the dog 16 inactive during transportation and handling of the vault preliminary to its sealing, any suitable means may be employed, that shown being a screw 20 on the dog 16 adapted to be impinged against the inner side of the closure B and unscrewed to release the dog when the closure B is ready to finally seal and close the open end of the vault body A. Obviously, when the closure B is finally placed into position with the dog 16 released, the spring 18 is free to engage the dog with the rack 19 when the bolts 3 are projected to engage the flange 2. No means being provided by which to unlock the dog 16 from the exterior, opening of the vault after its final sealing is effectively prevented.

If desired the outer end of the shaft part 9^a may project through a packing box of any suitable type carried by the outer end portion of the casing 14. This is to subserve the airtight action of the closure B.

Having thus described my invention what I claim as new is:

1. In a burial vault, the combination of 105 a vault body, a closure therefor, a locking means for the closure consisting of a series of locking bolts, and means to operate said bolts comprising a two part shaft on the closure, a pinion connected with one part of said shaft and engaging the locking bolts to operate the latter in one direction and a disk carried by said part of the shaft adapted to engage the bolts and move them in another direction, the other part of the shaft 110 being movable with the first named part to cause the pinion to actuate the bolts, and being movable relatively independently of said first named part to cause the disk to actuate the bolts, the pinion being arranged 115 to cause sliding movement of the bolts and the disk being arranged to cause a lever-like movement of the bolts.

2. In a burial vault, the combination of a vault body, a closure therefor, a locking 125 means for the closure consisting of a series of locking bolts, and means to operate said bolts comprising a two part shaft on the closure, a pinion connected with one part of said shaft and engaging the locking bolts 130

- to operate the latter in one direction and a disk carried by said part of the shaft adapted to engage the bolts and move them in another direction, the other part of the shaft being movable with the first named part to cause the pinion to actuate the bolts, and being movable relatively independently of said first named part to cause the disk to actuate the bolts, the pinion being arranged to cause sliding movement of the bolts and the disk being arranged to cause a lever-like movement of the bolts, the two parts of the shaft having a screw connection with one another and the first named part of the shaft having a boss abutting with the disk, the 15 disk being arranged in contact with portions of the bolts, and the two parts of the shaft being assembled so that movement of the second mentioned part causes abutment and simultaneous movement of the first mentioned part, while a different movement of the second mentioned part causes separation 20 action of the two parts of the shaft.
- 10
- In testimony whereof I affix my signature.

HENRY C. SPONHAUER.
